UNITED STATES PATENT OFFICE.

ROLLO M. VICK, OF DETROIT, MICHIGAN.

RECORD-CABINET.

984,051.

Specification of Letters Patent. Patented Feb. 14, 1911.

Application filed October 26, 1910. Serial No. 589,256.

To all whom it may concern:

Be it known that I, ROLLO M. VICK, a citizen of the United States, residing at Detroit, in the county of Wayne and State of Michigan, have invented a new and useful Record-Cabinet, of which the following is a specification.

My invention relates to improvements in devices for the systematic and convenient filing and keeping of records of various kinds, the records being made upon cards or slips and arranged in the device in the manner hereinafter more fully described.

More particularly the invention relates to a record cabinet and its parts, including the record slips and folders arranged in a drawer somewhat after the manner of a card index.

The objects of the invention are to generally improve devices of the character mentioned, to provide a record cabinet in which charge slips or other records may be conveniently kept in such way as to facilitate the inserting of additional or new records and the finding of any particular record when desired.

A further object of the invention is to hold the various records spaced from each other in such way that the individual records may stand out clearly and be readily found when desired, certain portions of the record cards being also visible when filed so that it is unnecessary to remove the charge slips or memorandums from the drawer in the cabinet in order to learn the most important fact concerning that record.

These objects, together with other objects readily apparent to those skilled in the art, I attain by the construction illustrated in the accompanying drawings, although my invention may be embodied in other forms, the construction illustrated being chosen by way of example.

In the drawings Figure 1 is a front perspective view of a drawer of a record cabinet embodying my invention, showing the same provided with a physician's credit record. Fig. 2 is a perspective view of one of my invented folders containing a physician's credit slip properly made out. Fig. 3 is a face view of one of the blank credit slips such as intended for use by a physician.

Fig. 4 is a front perspective view of one of the division plates. Fig. 5 is a longitudinal sectional view through a record cabinet 55 drawer embodying my invention, a portion of said drawer being broken away to reduce the size of the figure. Fig. 6 is a transverse sectional view taken on the line 6—6 of Fig. 5 showing one of the division plates locked 60 in the drawer. Fig. 7 is a transverse sectional view showing the division plate unlocked and partly removed. Fig. 8 is a transverse sectional view showing the front end of the drawer with the locking rod actuating device in locked position. Fig. 9 is a similar view showing the locking rod actuating device in unlocked position and with parts of the drawer broken away.

Throughout the several views similar reference numerals indicate similar parts.

The numeral 1 indicates the front of the drawer, 2 the sides and 3 the back. The bottom 4 is provided on the inside of the drawer with a median longitudinal channel 5 75 adapted to receive the lower projections on the division plates as hereinafter will appear.

Along the middle of the channel 5 extend the locking rods 6, 6 which are convexo-concave in cross section and arranged with their convex sides adjacent, each rod being pivotally connected at its ends near the lower edge of the rod to the front 1 and the back 3 as clearly illustrated at 7 in Fig. 5. It 85 will be understood that by a simultaneous rocking movement of the rods upon their pivotal connections the upper edges of said rods may be brought inwardly until the convex faces of the rods abut and said rods 90 stand as nearly vertically as possible or in unlocked position as in Fig. 9 or said rods may be rocked to throw their upper edges outwardly, away from each other into the separated or locking position shown in Fig. 95 8. It will be noted that in said locking position the two rods present a cross section of V-shape, with the sides of the V slightly inwardly curved toward each other, and that in the unlocked position, said rods are turned 100 so that their upper edges are as closely adjacent each other as their lower edges are in the locking position.

For the purpose of actuating the locking

rods the latch 8 is provided, which latch stands vertically on the inner side of the front 1 and is attached to said front by means of the screws 9 passing through a vertically disposed slot 10, which permits the latch to be raised or lowered by a sliding movement. For the purpose of presenting a convenient finger hold, the upper end of the latch 8 is bent backwardly or away from the front 1, forming the finger piece 11, which, as readily seen in Fig. 5, may be conveniently grasped for the purpose of raising or lowering the latch 8. On the screws 9 intermediate the latch 8 and the front 1 are spacing washers 12 for the purpose of holding the latch at a slight distance from the inner side of the said front. If desired a false front 13 may be arranged on the inside of the drawer, extending from side to side of the same, covering the latch 8 and screws 9 and presenting a smooth even surface on the inside toward the records.

The bottom end of the latch 8 extends downward into the channel 5 and at the extreme lower edge of said latch two upwardly extending outwardly curved slots 14 are arranged. Said slots are joined at the edge of the latch, thus providing a common slot at that point, but the upper ends of the slots are considerably separated and a depending, curved-sided separating tip 15 results from the peculiar shape and arrangement of the slots. Where the slots 14 extend through the lower edge of the latch 8 the sides of the combined slots are sufficiently close to each other so that when the latch is raised to the unlocked position illustrated in Fig. 9 said side edges will engage the upper edges of the locking rods 6 and move them into the unlocked position. When, however, the latch 8 is moved downwardly the upper edges of the rods 6 will be permitted to separate and the separating tip 15 moving down between the upper edges of said rods will produce a positive movement of the same into the extended or locking position shown in Fig. 8. It will be noted that the said locking position will normally be maintained by reason of the fact that the weight of the latch 8, although small, will tend to hold the latch in its downward position and any unlocking movement of the rods will be prevented by the tip 15 until such time as the latch 8 is raised.

On the outer side of the front 1 may be arranged a suitable pull 16 together with a label 17 if desired, said pull and label being of any well known form of construction.

Arranged in the drawer from front to back is a series of division plates 18 preferably formed from sheet metal having a lower projection 19 adapted to enter the channel 5. Said projection 19 is provided with a dove-tailed locking notch 20 opening through

the lower edge of the plate and having upwardly extending, outwardly inclined sides adapted to be engaged by the locking rods 6 when in the locking position, as illustrated in Fig. 6, said locking notch at the extreme lower edge of the plate, however, being of sufficient width to permit the plate to be removed from the drawer when the rods 6 are in the unlocked position, as illustrated in Fig. 7.

Each division plate is provided with a plurality of spacing springs 21, preferably four in number. Said springs should be turned toward the front 1 when the plates are in the drawer. Each spring consists of a small, curved strip of spring metal firmly connected at its upper end to the body of the division plate, curved outwardly and extending downwardly from the point of attachment, and having its lower free end formed rounding or curled so as to present a smooth, rounding surface at its most extremely forward portion. The purpose of this construction is to permit the ready insertion or withdrawal of records without the same catching on the ends of the springs and causing inconvenience.

An inspection of Fig. 5 will disclose how the spacing springs 21 serve to maintain the division plates in spaced relation to each other and in vertical position, said springs being so distributed over the division plates as to give several points of contact for the springs of each plate against the plate or records immediately in front thereof.

Attention is now directed to the folders used in the drawer. Each folder comprises a back portion 22 and a front portion 23. The back portion and front portion are connected by an integral folded portion 24 along the lower edge. The back portion 22 is of a width and height corresponding substantially to the width and height of the division plates 18. Formed integrally with the back portion 22 and extending above the upper edge of the same is the name tab 25 upon which may be written the name of a patient, client, customer, month, class of merchandise or other distinguishing word or symbol in accordance with the use to which the record cabinet is put. In the drawings said tabs are shown as bearing the names of various patients as the credit slips illustrated are intended for the use of a physician. The front portion 23 is of less height than the back portion 22 so that when the folders are arranged in the drawer as illustrated in Fig. 5, the upper portion of the credit slip will extend above the top edge of said front portion.

In Fig. 3 is illustrated one of the blank credit slips 26 for the use of a physician. Said slips may be printed on paper, each slip being of a width substantially equal to

the width of the folders and of a height equal to the back portion 22. At the top of the slip on the left hand side is a space 27 for the name of the patient. To the right of 5 said space 27 are spaces adapted for the record of financial transactions between physician and patient including spaces for charge, credit, etc., and in the extreme upper right hand corner, a space 28, in which may 10 be written the amount of balance due on account. Below the spaces at the top of the slip may be arranged appropriate spaces for the record of other facts concerning the case as may be desired.

15 When a slip 26 is made out the corresponding folder is readily found by reason of the alphabetical or other systematic arrangement of the folders in the drawer and the said slip placed in its appropriate 20 folder. In returning the folder to the drawer it should be placed immediately back of one of the division plates and pushed downwardly into place, the spacing springs 21 of the division plate immediately to the 25 rear pressing forwardly upon the folder and holding the same in contact with the back of the next forward division plate as illustrated in Fig. 5. In this way each folder is maintained in vertical position, the various 30 folders being uniformly spaced from each other so that the name tabs 25 may be conveniently read without necessitating the separating of the various records by the fingers of the hand as is usually necessary with 35 card systems and other similar recording devices now commonly in use.

The various division plates should preferably have a cut-out portion 29 in their upper edges so as to permit the various folders and 40 slips to be more readily removed when desired, as well as to permit the person using the credit cabinet to place his finger against the forward slip to separate the slips in the folder from the front portion 23 and the 45 division plate when inserting an additional slip into the folder, thus preventing the filing of new slips back of slips already filed when in fact each new slip should be placed in front of those previously filed. An additional 50 purpose of the cut-out portion 29 is to make visible a portion of the name space 27 of the credit slips in the folder immediately back of each division plate so as to readily detect any error in the filing 55 of credit slips in the wrong folder. This feature is clearly illustrated at 30 in Fig. 1, the folder bearing the name Elbert, R. L. being removed from said drawer and the upper edge of the slip bearing the name 60 Elkins, B. M. being visible as properly filed in the folder bearing the same name on the name tab.

The upper right hand corner of each division plate is cut away at 31 to permit the

various balance spaces 28 to be plainly visible when the credit slips are filed, as shown in Fig. 1. In said figure, for instance, it may be readily seen that the balance due upon B. M. Elkins' account is \$4.50, and that the balance due upon the account of 70 F. L. Clark is \$7.00. If preferred the division plates may be made of a height only equal to the front portion 23 of the folders so that the entire top edge of the front charge slip in the folder immediately back 75 of each division plate would be readily seen. The preferable form, however, is that illustrated in the drawings wherein only the curved cut-out portion and the cut-out portion at 31 are employed. 80

In the use of a credit cabinet such as described and shown in the drawings it is preferable to have the charge slips 26 made up in pads so that as each slip is made out it can be separated from the pad and either 85 put into its appropriate folder immediately or laid aside until a number of such slips have been made out, when all of the same may be placed in their appropriate folders at the same time. In making out each slip 90 the previous balance should be carried forward from the last slip made out for the same patient. This forwarded amount should be placed in the space marked "For'd." at the top of the slip. The amount 95 of the charge should then be written in the charge space underneath marked "Ch." and the total carried forward to the space marked "Amt." Any credit should be arranged in the credit space, marked "Cr." 100 and the balance carried over into the space 28 marked "Bal." The record in Fig. 2 will thus show that the previous balance was \$26.50, that for a call on October 24, 1906, a charge of \$1.50 was made, that on the same 105 day a payment of \$10.00 was made, making the balance due \$18.00. This balance will show up in the drawer in such manner that it may be seen immediately when desired without removing any of the records from 110 the folder, the division plates being so separated that the names on the tabs 25 are very easily read and the cut-out corners of the division plates at 31 disclosing the balance on the most forward slip in the folder. It 115 is of course important that the last slip made out should be placed in front of all previous slips in the folder, so that the latest balance will show without removing either folder or slips. 120

It will be understood that when all of the division plates 18 are properly in place within the drawer and the latch 8 is in the lowered, locked position, all of the said plates will be locked in the drawer, the various 125 folders, however, being readily removed. By the mere lifting of the latch 8, however, all of the division plates are instantly un-

locked, and any of the said plates may then be removed, thus making the changing about of records or the addition of new records and folders very easy. In the drawer shown 5 in Fig. 1, for instance, if "R. L. Elbert's" account has been closed and it is desired to remove that folder from among the active accounts not only the folder and slips shown in Fig. 2 should be removed, but also 10 the division plate immediately in front of the Elbert folder should be removed. This will bring the "B. M. Elkins" folder up to a position immediately back of the "L. A. Dowling" folder, and the records and division plates removed may be readily transferred to another part of the drawer or otherwise disposed of. New accounts are as 15 easily inserted at their appropriate places in the drawer.

20 While I have shown the device as adapted to the use of a physician in the keeping of his accounts, it will be apparent that the device is equally well adapted to a very large number of other purposes including 25 the keeping of accounts in mercantile establishments as well as the recording of other facts where it is desirable to have the various divisions, folders or cards separated and easily found when desired.

30 I claim:

1. A record cabinet comprising a container, spring separated division plates arranged in series in said container, means adapted to lock said division plates in said 35 container, record slips provided with record spaces at their top edges and adapted to be arranged between adjacent division plates of the series and said division plates, provided with cut-away portions adapted to 40 permit said record spaces to be seen when said slips are arranged between said plates.

2. A record cabinet comprising a container, spring separated division plates arranged in series in said container, record 45 slips provided with record spaces and adapted to be arranged between adjacent division plates of the series, record space portions of said record slips extending above said division plates, and adapted to be seen 50 when said slips are arranged between said plates in said container.

3. A record cabinet comprising a container, spring separated division plates arranged in series in said container, means 55 adapted to lock said division plates in said container, folders adapted to be arranged between adjacent division plates of the series, said folders provided with back and front portions, record slips provided with 60 record spaces at their top edges and adapted to be arranged in said folders between said back and front portions, said front portions of less height than said record slips, and said separated division plates being cut

away at their top edges, whereby, when said 65 record slips and folders are between said division plates, said spaces on said slips may be seen without removing said slips or folders.

4. In a record cabinet, in combination 70 with record slips provided with record spaces at their top edges, spring separated division plates provided with cut-out portions adapted to permit said record spaces to be seen when the record slips are ar- 75 ranged between said division plates.

5. A record cabinet comprising a container, a plurality of transversely disposed, vertical division plates arranged in series in said container, each plate provided with 80 spacing springs adapted to maintain the various plates in spaced relation to each other, means for locking said division plates in said container and record slips of a height greater than the height of said di- 85 vision plates and provided at their upper edges with spaces for containing records, whereby said upper portions of said record slips are visible when said slips are in said container between said division plates. 90

6. A record cabinet comprising a container, a plurality of transversely disposed, vertical division plates arranged in series in said container, said plates provided with spring means adapted to maintain the vari- 95 ous plates in spaced relation to each other, means for locking said division plates in said container, folders adapted to be ar- ranged between the division plates and record slips adapted to be arranged in said 100 folders, each folder comprising a back portion and a front portion, said front portion being of less height than said back portion, said record slips being of greater height than said front portion and said di- 105 vision plates provided with cut-out portions adapted to permit the upper portions of said record slips to be seen when the said folders and slips are arranged between said division plates. 110

7. A device of the character described comprising a series of division plates, each plate provided with spacing springs adapt- 115 ed to maintain said division plates in spaced relation and in vertical position, folders 115 adapted to be arranged between the various division plates, each folder comprising a back portion and a front portion connected at the bottom by an integral folded portion, said back portion being of a height equal 120 to the height of the division plates and hav- 120 ing an integral name tab extending above the upper edge of said division plates, the front portion of a height less than the height of the back portion, record slips of 125 a height greater than the height of said front portion but not greater than the height of said back portion and provided

at their upper edges with spaces for items of record, and said division plates cut away at their top edges, whereby the said spaces on said record slips are visible without removing said folders or said slips from between said division plates.

In testimony that I claim the above, I

have hereunto subscribed my name in the presence of two witnesses.

ROLLO M. VICK.
